US0D1066724S

(12) **United States Design Patent** (10) Patent No.: **US D1,066,724 S**
Wan (45) Date of Patent: **** Mar. 11, 2025**

(54) **STERILIZER**

(71) Applicant: **Shenzhen Soocas Technology Co., Ltd.**, Shenzhen (CN)

(72) Inventor: **Qingtan Wan**, Guangdong (CN)

(**) Term: **15 Years**

(21) Appl. No.: **35/519,214**

(22) Filed: **Sep. 28, 2023**

(80) **Hague Agreement Data**

Int. Filing Date: **Sep. 28, 2023**
 Int. Reg. No.: **DM/233306**
 Int. Reg. Date: **Sep. 28, 2023**
 Int. Reg. Pub. Date: **Dec. 1, 2023**

(30) **Foreign Application Priority Data**

(57) **CLAIM**

The ornamental design for a sterilizer, as shown and described.

DESCRIPTION

Fig. 1.1 is a front view of a sterilizer showing our new design;

Fig. 1.2 is a perspective open view thereof;

Fig. 1.3 is a back view thereof;

Fig. 1.4 is a left side view thereof;

Fig. 1.5 is a right side view thereof;

Fig. 1.6 is a top view thereof;

Fig. 1.7 is a bottom view thereof;

Fig. 1.8 is a perspective view thereof;

Fig. 1.9 is a front open view thereof; and

Fig. 1.10 is another perspective open view thereof.

The portions of sterilizer shown in broken lines form no part of the claimed design.

1 Claim, 10 Drawing Sheets
